UNITED STATES PATENT OFFICE.

CLARENCE W. LUCAS, OF DECATUR, ILLINOIS, ASSIGNOR TO THE PHOENIX GLASS COMPANY, OF PITTSBURGH, PENNSYLVANIA, A CORPORATION OF WEST VIRGINIA.

HOLDER FOR LIGHTING-FIXTURES.

1,316,250.

Specification of Letters Patent. Patented Sept. 16, 1919.

Application filed January 27, 1916. Serial No. 74,520.

To all whom it may concern:

Be it known that I, CLARENCE W. LUCAS, a citizen of the United States, residing at Decatur, in the county of Macon and State 5 of Illinois, have invented a certain new and useful Improvement in Holders for Lighting-Fixtures, of which the following is a specification.

My invention relates to that class of devices which are designed to support an inverted shade at the bottom and a reflector at the top.

Devices of this character, with which I am familiar, have a harp-like structure which 10 extends from the lower shade support to the upper, and is secured to the lower by means of rivets or is soldered. Inasmuch as the material of which the upper shade is formed is very thin, there is a continual danger of 15 the rivets pulling out, and it is also difficult to hold the fixture in a vertical position. These devices also fail to provide sufficient means for ventilation, with the result that when the new, so called, nitrogen light is 20 used, they become over-heated.

My invention has for its object to provide a structure which will overcome the foregoing objections, and which will provide a holder which will be very strong and rigid, 25 which will have ample ventilation, and which will provide means to prevent the unscrewing of the upper shade clamping means, except by manual operation.

Other objects of the invention may appear in the hereinafter contained claims and description.

My means of obtaining the foregoing objects may be more readily understood by having reference to the accompanying drawings which are hereunto annexed and are a part of this specification, in which:

Figure 1 is a vertical elevation with the securing rings removed.

Fig. 2 is a top or plan view of the same, 45 the top being open.

Fig. 3 is a perspective view of the upper locking ring.

Fig. 4 is a perspective view of the lower locking ring.

Fig. 5 is an assembled view, part of the holder being broken away.

Similar reference numerals refer to similar parts throughout the entire description.

As shown in the drawings, the holder is

provided with a lower shade holding means 55 5, which has secured thereto, two upwardly extending members hereinafter referred to as the harp 6. The bolt 7 projects downwardly from the center of the shade-clamping member, and carries a cup or shell 8, 60 designed to engage the lower shade. It is secured into position by means of a knob 9, mounted upon the bolt 7. The harp 6 extends outwardly and has secured thereto an upper shade holding means 10, which is 65 formed with a peripheral flange 12, and has two slots 13 cut or formed in the sides thereof, the upper edge of which is provided with serrations or teeth 11. A groove or recess 14 is formed in the vertical wall of the upper shade holder, adjacent the upper end 70 of the slot 13.

In the devices with which I am familiar, the harp terminates at this point, but in my device, I extend the ends 15 upwardly until 75 they engage a cap 16 which is formed with a hemispherical top portion 17, a horizontal shoulder 18 and a vertical cylindrical portion. The upper ends of the harp are riveted to the vertical cylindrical portion, 80 and the ends 20 project upwardly through the horizontal shoulder, and these ends are slotted as more clearly seen in the detailed view. A segment 21 of the cap 16 is provided with a hinge 22 which is secured by 85 a pin or pivot 23 to the vertical shoulder on the remaining portion, permitting it to swing horizontally and outwardly when it is desired to attach or detach the holder to an electric light socket. 90

Two vertical grooves 24 are formed in the vertical cylindrical portion of the cap to permit the collar 25 which clamps the upper shade in position to be passed over it. This collar is provided with two inwardly 95 projecting lugs 26 which are fitted to and coincide with the grooves 14 and 24 and are adapted to engage the serrations in the slots 13 formed in the upper shade holding member 10. A ring 27 having an inturned flange 28, fits over the cap 16, and is provided with two slots 29 diametrically opposite to each other, which taper toward one end, the larger end 30 fitting to and coinciding with the upper ends 20 of the harp 6, the two sides of the slots being adapted to engage the grooves cut adjacent the ends 20 of the harp 6, so that by placing the ring 100 105

over the cap, the ends 20 of the harp 6, project through these openings 30, when rotation of the ring 27 will cause the sides of the slots 29, to enter the grooves adjacent 5 the ends 20 of the harp 6, and the farther the ring 27 is twisted, the tighter this engagement will be, which thus has the effect not only of locking the pivoted segment 21 into position, but also lessens the possibility 10 of the harp structure 6 being drawn out of the holder.

It will be obvious from the foregoing description that there is a wide space open to the atmosphere between the upper shade 15 holding means and the cap, which space amply provides for ventilating and cooling the holder.

As shown in Fig. 5, the lower shade 31 is held in position between the cup or shell 20 8, and the lower shade holding means 5, the knob 9 serving to clamp them firmly together; the upper shade 32 is then placed on the upper shade holding means resting on the peripheral flange 12. The collar 25 25 is passed over the cap 16, the vertical grooves 24 permitting the lugs 26 to pass freely. The lugs 26 are then placed through the grooves or recesses 14 into the inclined slots 13, when the rotation of the collar 25 30 causes it to clamp and hold the upper shade 32, the teeth or serrations preventing its working loose. The ring 27 is then placed on the wire 33 above the electric socket 34 and the segment 21 is opened, and the socket 35 35 can be placed in position without the necessity of removing the shades. The segment 21 is then closed and the ring 27 is placed over the cap 16 with the openings 30 in position to register with the ends 20 of the harp 6. These permit the ring to drop over the said ends 20 and bring the edges of the slots 29 in register with the grooves cut adjacent the ends 20 of the harp 6, when the rotation of the ring causes the edges to 40 45 enter the said grooves, and this has the effect of binding the ring securely on the cap, besides strengthening the resistance of the harp 6, to its being pulled downwardly or loosened.

50 Having described my invention what I regard as new and desire to secure by Letters Patent, is:

1. In a holder for lighting fixtures, the combination with lower shade holding means, of a frame extending upwardly therefrom, an upper shade holding means having a peripheral flange secured to said frame, there being inclined slots formed in said shade holding means, teeth cut on the 55 60 edge of said slots, a collar, lugs thereon which fit the said slots and engage said teeth, a cap spaced from said upper shade holding means, a segment of said cap being hinged thereto and swinging horizontally, 65 said cap having a shoulder and a vertical

cylindrical portion, the ends of the frame passing through said shoulder and the vertical portion of the cap being fastened to said frame, there being grooves formed in said frame adjacent the ends thereof, a ring 70 having an inturned flange, there being tapered slots in said flange the larger ends of which correspond in size to the ends of the frame, the edges of the slots being adapted to engage the grooves adjacent the 75 ends of the frame.

2. In a holder for lighting fixtures, the combination with lower shade holding means, of a frame extending upwardly therefrom, an upper shade holding means 80 having a peripheral flange secured to said frame, there being inclined slots formed in said shade holding means, teeth cut on the edge of said slots, a collar, lugs thereon which fit the said slots and engage said 85 teeth, a cap spaced from said upper shade holding means, there being grooves formed in said cap to permit said collar to pass over the cap, a segment of said cap being hinged thereto, and swinging horizontally, 90 said cap having a shoulder and a vertical cylindrical portion, the ends of the frame passing through said shoulder and the vertical portion of the cap being fastened to said frame, there being grooves formed in 95 said frame adjacent the ends thereof, a ring having an inturned flange, there being tapered slots in said flange the larger ends of which correspond in size to the ends of the frame, the edges of the slots being adapted to engage the grooves adjacent the ends of the frame. 100

3. In a holder for lighting fixtures, the combination with lower shade holding means, of a frame extending upwardly 105 therefrom, an upper shade holding means having a peripheral flange secured to said frame, there being inclined slots formed in said shade holding means, and grooves leading to said slots, teeth cut on the edge of said slots, a collar, lugs thereon which fit the said slots and engage said teeth, a cap spaced from said upper shade holding means, there being grooves formed in said 110 cap to permit said collar to pass over the cap, a segment of said cap being hinged thereto and swinging horizontally, said cap having a shoulder and a vertical cylindrical portion, the ends of the frame passing through said shoulder and the vertical portion of the cap being fastened to said frame, there being grooves formed in said frame adjacent the ends thereof, a ring having an inturned flange, there being tapered slots in 115 120 said flange the larger ends of which correspond in size to the ends of the frame, the edges of the slots being adapted to engage the grooves adjacent the ends of the frame.

4. In a holder for lighting fixtures, the combination with lower shade holding 130

- means, of a frame extending upwardly therefrom, two spaced circular members thereon, the lower one furnishing a holder for the upper shade, the upper circular member having a segment hinged thereto and adapted to swing horizontally, and means to hold said segment in a closed position, said means engaging and holding the upper ends of said frame.
5. In a holder for lighting fixtures, the combination with lower shade holding means, of a frame extending upwardly therefrom, two spaced circular members thereon, the lower one furnishing a holder for the upper shade, the upper circular member having a segment hinged thereto and adapted to swing horizontally, means to hold said segment in a closed position, said means engaging and holding the upper ends of said frame, and means to clamp said shade to the shade support.
6. In a holder for lighting fixtures, the combination with lower shade holding means, of a frame extending upwardly therefrom, two spaced circular members thereon, the lower one furnishing a holder for the upper shade, the upper circular member having a segment hinged thereto and adapted to swing horizontally, means to hold said segment in a closed position, said means engaging and holding the upper ends of said frame, means to clamp said shade to the shade support, and means to lock said clamping means in position.
35. 7. In a holder for lighting fixtures, the combination with lower shade holding means, of a frame extending upwardly therefrom, an upper shade holding means having a peripheral flange secured to said frame, a cap spaced from said upper shade holding means, a segment of said cap being hinged thereto and swinging horizontally, said cap having a shoulder and a vertical cylindrical portion, the ends of the frame passing through said shoulder and the vertical portion of the cap being fastened to said frame, there being grooves formed in said frame adjacent the ends thereof, a ring having an inturned flange, there being tapered slots in said flange the larger ends of which correspond in size to the ends of the frame, the edges of the slots being adapted to engage the grooves adjacent the ends of the frame.
8. In a holder for lighting fixtures, the combination with lower shade holding means, of a frame extending upwardly therefrom, an upper shade holding means having a peripheral flange secured to said frame, there being inclined slots formed in said shade holding means, teeth cut on the edge of said slots, a collar, lugs thereon on which fit the said slots and engage said teeth, a member at the top of said frame, in spaced relation to the shade holding means, a segment hinged thereto and adapted to swing horizontally, and means to hold said segment in a closed position, said means engaging and holding the upper ends of said frame.

In testimony whereof I have signed the foregoing specification.

CLARENCE W. LUCAS.
